(57) CLAIM

The ornamental design for a female enteral coupling, substantially as shown and described.

DESCRIPTION

FIG. 1 is a top perspective view of a female enteral coupling according to an example embodiment of the present invention.

tion, the female enteral coupling shown in use with an unclaimed enteral syringe body lid.

FIG. 2 is a right side plan view of the female enteral coupling of FIG. 1.

FIG. 3 is a left side plan view of the female enteral coupling of FIG. 1.

FIG. 4 is a bottom plan view of the female enteral coupling of FIG. 1.

FIG. 5 is a top plan view of the female enteral coupling of FIG. 1.

FIG. 6 is a cross-sectional view of the female enteral coupling of FIG. 1, as viewed from line 6 identified in FIG. 5.

FIG. 7 is a top perspective view of a female enteral coupling according to another example embodiment of the present invention, the female enteral coupling shown in use with an unclaimed enteral syringe body lid.

FIG. 8 is a right side plan view of the female enteral coupling of FIG. 7.

FIG. 9 is a left side plan view of the female enteral coupling of FIG. 7.

FIG. 10 is a bottom plan view of the female enteral coupling of FIG. 7.

FIG. 11 is a top plan view of the female enteral coupling of FIG. 7.

FIG. 12 is a cross-sectional view of the female enteral coupling of FIG. 7, as viewed from line 12 identified in FIG. 11.

FIG. 13 is a top perspective view of a female enteral coupling according to another example embodiment of the present invention, the female enteral coupling shown in use with an unclaimed enteral syringe body lid.

FIG. 14 is a right side plan view of the female enteral coupling of FIG. 13.

FIG. 15 is a left side plan view of the female enteral coupling of FIG. 13.

FIG. 16 is a bottom plan view of the female enteral coupling of FIG. 13.

FIG. 17 is a top plan view of the female enteral coupling of FIG. 13; and,

FIG. 18 is a cross-sectional view of the female enteral coupling of FIG. 13, as viewed from line 18 identified in FIG. 17. Portions shown in broken lines are for illustrative purposes only and form no part of the claimed design.
